BRACKET FOR LANTERNS

Filed June 5, 1929

INVENTOR

RALPH PANZA

BY Raymond L. Barton

ATTORNEY

UNITED STATES PATENT OFFICE.

RALPH PANZA, OF LOS ANGELES, CALIFORNIA.

DESIGN FOR A BRACKET FOR LANTERNS.

Application filed June 5, 1929. Serial No. 31,556. Term of patent 7 years.

To all whom it may concern:

Be it known that I, RALPH PANZA, a citizen of the United States, residing at Los Angeles, in the county of Los Angeles and State of California, have invented a new, original and ornamental Design for a Bracket for Lanterns, of which the following is a specification, reference being had to the accompanying drawing, forming part thereof.

The figure is a perspective view of a bracket for lanterns showing my new design.

I claim:

The ornamental design for a bracket for lanterns, substantially as shown.

RALPH PANZA.
